Filed Feb. 5, 1970, Ser. No. 21,288

Term of patent 14 years

Int. Cl. D31

U.S. Cl. D72—1

FIG. 1 is a perspective view of a drink-refill signalling bell showing my new design;

FIG. 2 is a front elevational view thereof;

FIG. 3 is an elevational view of one side thereof, the opposite side view being identical;

FIG. 4 is a rear elevational view thereof; and

FIGS. 5 and 6 are respectively top and bottom plan views thereof.

The glass is shown in broken lines in FIG. 1 for illustrative purposes only.

I claim:

The ornamental design for a drink-refill signalling bell, as shown and described.
